(57) **CLAIM**

The ornamental design for a wellbore tool with extendable arms, as shown and described.

DESCRIPTION

FIG. 1 is a top perspective view of a wellbore tool with extendable arms showing our new design with the arms in

the fully extended position with an unclaimed ballast at the bottom and an unclaimed connecting segment at the top; FIG. 2 is a bottom perspective view of a wellbore tool with extendable arms of FIG. 1;

FIG. 3 is a side elevation view of the wellbore tool with extendable arms of FIG. 1;

FIG. 4 is another side elevation plan view of the wellbore tool with extendable arms of FIG. 1;

FIG. 5 is a top plan view of the wellbore tool with extendable arms of FIG. 1;

FIG. 6 is bottom plan view of the wellbore tool with extendable arms of FIG. 1;

FIG. 7 is another side elevation view of the wellbore tool with extendable arms of FIG. 1;

FIG. 8 is another side elevation view of the wellbore tool with extendable arms of FIG. 7;

FIG. 9 is a close-up and top perspective view of the wellbore tool with extendable arms of FIG. 1 without the unclaimed ballast at the bottom and the unclaimed connecting segment at the top;

FIG. 10 is a close-up and bottom perspective view of the wellbore tool with extendable arms of FIG. 9;

FIG. 11 is a close-up and side elevation view of the wellbore tool with extendable arms of FIG. 9;

FIG. 12 is another close-up and side elevation view of the wellbore tool with extendable arms of FIG. 9;

FIG. 13 is a close-up and top plan view of the wellbore tool with extendable arms of FIG. 9;

FIG. 14 is a close-up and bottom plan view of the wellbore tool with extendable arms of FIG. 9;

FIG. 15 is another close-up and side elevation view of the wellbore tool with extendable arms of FIG. 9;

FIG. 16 is another close-up and side elevation view of the wellbore tool with extendable arms of FIG. 9;

FIG. 17 is a top perspective view of the wellbore tool with extendable arms of FIG. 1 with the arms in a partially extended position and with the unclaimed ballast at the bottom and the unclaimed connecting segment at the top; FIG. 18 is a side elevation view of the wellbore tool with extendable arms of FIG. 17;

FIG. 19 is a top perspective view of the wellbore tool with extendable arms of FIG. 17

(Continued)

FIG. 20 is a close-up and top perspective view of the wellbore tool with extendable arms of FIG. 17 without the unclaimed ballast at the bottom and the unclaimed connecting segment at the top;
 FIG. 21 is a close-up and side elevation view of the wellbore tool with extendable arms of FIG. 17;
 FIG. 22 is a close-up and top plan view of the wellbore tool with extendable arms of FIG. 17;
 FIG. 23 is a top perspective view of the wellbore tool with extendable arms of FIG. 1 with the arms in a fully retracted position and with the unclaimed ballast at the bottom and the unclaimed connecting segment at the top;
 FIG. 24 is a side elevation view of the wellbore tool with extendable arms of FIG. 23;
 FIG. 25 is a top perspective view of the wellbore tool with extendable arms of FIG. 23; and,
 FIG. 26 is a close-up and top perspective view of the wellbore tool with extendable arms of FIG. 23 without the unclaimed ballast at the bottom and the unclaimed connecting segment at the top.
 The broken lines in the following figures are fully disclosed but presently unclaimed portions of the design.

1 Claim, 15 Drawing Sheets
